United States Patent Office.

ALBERT STUCKENRATH, OF NEW YORK, N. Y.

Letters Patent No. 60,804, dated January 1, 1867.

IMPROVEMENT IN CUT-OFFS FOR STEAM ENGINES.

The Schedule referred to in these Letters Patent and making part of the same.

TO ALL WHOM IT MAY CONCERN:

Be it known that I, ALBERT STUCKENRATH, of the city, county, and State of New York, have invented a new and useful Improvement in the Mode of Operating Steam or other Cut-Offs, at the same time showing the number of horse-power, &c., by means of a graduated dial; and I hereby declare the following to be a full, clear, and exact description thereof, reference being had to the accompanying drawings, which are lettered to correspond with and constitute a part of the specification.

In order that the public may fully understand the nature of my improved invention, and those skilled in the construction and operation of the steam engine be enabled to construct and use the same, I will describe it as follows, to wit:

Figure 1 is a perspective drawing of a vertical section of the steam chest which contains the cut-off, and my improved mode of operating the same.

Figure 2 is a perspective drawing of a forked lever, L, having four prongs or projecting points, 1 2 3 4, which sustain and adjust the movable ring, R, by means of arms, d d'.

Figure 3 is a perspective drawing of the steam chest S, and graduated dial-plate D, showing the connecting-rod or lever, e e', and governor, f.

My invention does not consist in constructing a cut-off for steam engines, nor of the arrangement of a right and left-handed screw to operate the cut-off valve by means of "dogs and springs;" neither does it consist in adjusting the cut-off from the outer side of the steam chest S, nor attaching an index to the end of the cut-off valve-rod, n, as they are fully set forth in my application for a patent allowed May the first, 1866, and numbered 54,439; but the novelty of my present improvement does consist in the construction and arrangement of a lever, L, having four prongs or projecting points, 1 2 3 4, by which means it (the lever) operates the adjustable or movable ring R, which reciprocates upon the rod n, when acted upon by the lever L, whose fulcrum, F, runs transversely across and is secured to the sides of the steam chest S, or otherwise. The lever L is operated by the action of the main valve, by which means the desired motion is given to the cut-off.

The superiority of the above-stated improvement over the dogs, and springs, and other appliances for operating the cut-off valves of a steam or other engine, is that the pronged lever L is not affected by superheated steam, as is the case with the springs that operate the falls (or dogs); at the same time I believe a more uniform action is produced and retained by means of the lever L and movable ring R, than by any other device employed for such purposes; therefore,

What I claim as novel and useful, and what I wish to secure by Letters Patent of the United States of North America, is—

The lever L, adjustable ring R, constructed substantially as and for the purpose set forth and shown in the accompanying drawings.

I also claim the combination of the pronged lever L, adjustable ring R, levers u, and index of the graduated dial D, substantially as set forth.

In testimony whereof I hereunto subscribe my name in the presence of two witnesses.

ALBERT STUCKENRATH.

Witnesses:

JAMES P. MCLEAN,
WILLIAM WALDRON.
